UNITED STATES PATENT OFFICE.

VICTOR H. DILL, OF DAYTON, OHIO.

MOORING MAST FOR AIRSHIPS.

Application filed June 9, 1923. Serial No. 644,482.

To all whom it may concern:

Be it known that I, VICTOR H. DILL, a citizen of the United States, residing at Dayton, in the county of Montgomery and State of Ohio, have invented certain new and useful Improvements in Mooring Masts for Airships, of which the following is a specification.

This invention relates to mooring masts for airships, the object in view being to provide practical, safe and convenient operable means for anchoring or mooring an airship, particularly of the lighter-than-air type, to a mast, the construction embodying means whereby the usual rolling and pitching movements of the craft are provided for, the mooring mechanism counterbalanced and the mast as a whole being adapted for easy assembly, erection and demounting.

With the above and other objects in view, the invention consists in the novel construction, combination and arrangement herein fully described, shown and claimed.

In the accompanying drawings—

Figure 1 is a side elevation of the mast complete with all its equipment, showing the means for bracing or staying the mast and also showing a shock absorbing assembly for the anchor line of the airship;

Figure 2 is an enlarged side elevation, partly in section of the mast head, bumper head and upper portion of the mast showing also the bumper ring and its supporting means, together with the anchor line and the nose portion of a dirigible;

Figure 3 is a further enlarged longitudinal section through the bumper head and adjacent parts;

Figure 4 is an enlarged vertical diametrical section through the mast cap and mast head;

Figure 5 is a section through the mast head taken at a right angle to Figure 4;

Figure 6 is a plan view, partly in section, of another form of bumper head;

Figure 7 is a side view of the same partly in section.

Referring first to Figure 1 of the drawings, 10 represents the mast proper which may be of any suitable height and which is preferably made in separable sections connected by suitable joints 11. The mast 10 has at its lower end a dove-tail shaped block 12 which is removably seated in a mast step 13 supported by a foot block 14, shown em-

bedded or set into the ground. Guys 15 extend from the mast cap 16 at the top of the mast downwardly and outwardly to the ground where they are secured to suitable ground anchors 17. Bracing lines 18 extend from lugs 19 on the base of the mast to coupling members 20 which connect into the guys 15 at points intermediate the length thereof.

Referring now more particularly to Figures 2, 3, 4 and 5, the cap 16 is of tubular or hollow formation, as best shown in Figure 4, and has mounted therein a mast head 21, of elbow formation and hollow or tubular in order to allow the anchor line, hereinafter referred to, to pass therethrough. The mast head 21 has a cylindrical or journal portion 22 which extends through the mast cap 16 and is mounted in anti-friction supporting bearings 22 and also in top and bottom radial thrust anti-friction bearings 23 and 24. The mast head 21 is held against longitudinal movement within the mast cap by means of a key 25 shown in the form of a screw, the inner end of which is reduced to form a pin-like projection 26 which lies in an angular groove 27 in the lower end portion of the journal 21 of the mast head. The mast cap 16 is formed with a head flange 28 by means of which it is secured rigidly to the top of the mast 10, a flange 29 extending around the mast head 21 just above the mast cap 16 excludes the weather. It will now be observed that the mast head 21 is capable of complete rotation around a vertical axis while supported and retained in position by the mast cap. To the mast head, the bumper head 30 is pivoted on the shaft 30'.

The bumper head 30, in the preferred form thereof, comprises a hollow or tubular body 31 of cylindrical formation, having one end thereof reduced to form a spindle-like portion 32 which is surrounded by a loose sleeve 33 forming the hub of a spider which carries the bumper ring, hereinafter referred to. The sleeve 33 is held in place between bearing shoulders and bushings 34 and 35 and is capable of being removed by the displacement of a stud collar 36 held around the end of the spindle portion 32 by a screw 37 or equivalent fastening device. Connected by pivots 38 to lugs 39 arranged in a circular series around the sleeve 33, are spider arms 40, the arrangement of which is clearly shown in Figures 1 and 2. The

outer extremities of the spider arms 40 are connected by fasteners 41 to a bumper supporting ring 42 which may be formed of angle iron divided into two parts for convenient assembly. Seated in the bumper ring 42 is an annular cushion or bumper ring 43 comprising a tubular casing, as illustrated in Figure 2, said casing being stuffed with cushioning material, such, for example, as horse hair. The gas bag or aerostat 44 of the airship is shown as provided with an impact ring 44' of spruce or other suitable material adapted to rest in contact with the bumper cushion 43 when held by the anchor line which is shown at 45.

The anchor line 45 is shown as having a bridle 46, the extremities of which are attached at 47 to the bag 44. The anchor line 46 passes through a small guide ring 48 from which stays 49 extend outwardly where they are attached at 50 to the bumper ring 42. Yieldable means, such as spring 51, are incorporated in the stays 49 to provide flexibility and enable the ring 48 to accommodate itself to the bridle 46. This enables the gas bag to be held snugly and yet flexibly against the bumper ring. The spider arms 40 are further strengthened by braces 52 secured at their inner ends to the sleeve 33 and at their outer extremities to said spider arms, as clearly shown in Figure 2.

The anchor cable 45 extends from the bag through the eye 48 and into the bumper head where it passes around a sheave 53 having a grooved periphery 54, as shown in Figure 5. The shaft 55 of the sheave is carried by the mast head 16, as best shown in Figure 2, so that the periphery of the sheave is in line with the longitudinal centers of the mast cap 40 and the bumper head, or in other words the periphery of the sheave is maintained at all times in the pitch line of the anchor line. This is clearly shown in Figure 2. The anchor line 45, after passing around the sheave 53 extends downwardly through the center of the mast, as shown in Figures 1 and 2 and under a guide pulley 56 adjacent to the bottom of the mast and thence laterally around a shock absorbing assembly, designated generally at 57 and not particularly described as it forms no part of the present invention. The bumper head 30, at its rear end, is formed with a socket 58 into which is inserted one end of a counter-weight arm 59 held in the socket 58 by suitable fasteners 60, such as a pin or bolt. The counter-weight arm is adapted to receive any number of weights 61 sufficient to counterbalance the weight of the bumper ring and its cushion and the spider arms 40. In this way the bumper head is perfectly balanced so that it may freely accommodate itself to the pitching and rolling movements of the dirigible or airship.

In Figures 6 and 7, there is illustrated a

modified form of bumper head, the same being designated 62. Under the construction shown in said Figures 6 and 7 the sleeve 33 is dispensed with, and the spider arms 40 are connected to lugs 64 formed integrally with one end of the bumper head, the counterbalance arm 59 being fastened into the other end of the bumper head in the same manner as described in connection with Figure 3. The construction shown in the preceding figures, and hereinabove described, is preferred as it takes care of the rolling movements of the airship, giving greater freedom and flexibility and thereby more securely and safely mooring the ship.

The complete structure, by reason of the construction described, is capable of being quickly erected and taken down and furthermore, the parts thereof may be easily disconnected and the whole device compactly stored and made ready for transportation in a motor truck or vehicle. Due to the particular manner of mounting the mast head and bumper head and also due to the special arrangement of the sheave 53, the length of the anchor line is kept practically constant, thus avoiding a checking action on the part of said anchor line should the bumper head oscillate under the ducking action of the airship. The mast head is free to rotate about a vertical axis so that the airship is held head on to the wind irrespective of the direction in which the wind is blowing.

I claim—

1. An airship mooring mast embodying a mast, a mast head rotatable on a vertical axis at the top of the mast, a bumper head pivotally mounted on the mast head on a horizontal axis, said bumper head being balanced upon said pivot and an anchor line 100 reeved through the mast, mast head and bumper head.

2. An airship mooring mast embodying a mast, a mast head rotatable on a vertical axis at the top of the mast, a bumper head pivotally mounted on the mast head on a horizontal axis, said bumper head being balanced upon said pivot and an anchor line 110 reeved through the mast, mast head and bumper head, the mast head and bumper head being of tubular formation to admit the anchor line.

3. An airship mooring mast embodying a mast, a mast head rotatable on a vertical axis at the top of the mast, a bumper head pivotally mounted on the mast head on a horizontal axis, counterbalancing means for said bumper head, and an anchor line reeved through the mast, mast head and bumper head.

4. An airship mooring mast embodying a mast, a mast head rotatable on a vertical axis at the top of the mast, a bumper head pivotally mounted on the mast head on a horizontal axis, a bumper ring revolvable on 130

the bumper head, and an anchor line reeved through the mast, mast head and bumper head.

5. An airship mooring mast embodying
5 a mast, a mast head rotatable on a vertical axis at the top of the mast, a bumper head pivotally mounted on the mast head on a horizontal axis, counterbalancing means for said bumper head, a cushioning ring carried
10 by the bumper head, and an anchor line reeved through the mast, mast head and bumper head.

6. An airship mooring mast embodying
a mast, a mast head rotatable on a vertical
15 axis at the top of the mast, a bumper head pivotally mounted on the mast head on a horizontal axis, a revolvable bumper ring carried by the bumper head, and an anchor line reeved through the mast, mast head and
20 bumper head.

7. An airship mooring mast embodying
a mast, a mast head rotatable on a vertical axis at the top of the mast, a bumper head pivotally mounted on the mast head on a
25 horizontal axis, a bumper ring carried by said bumper head, a guide ring supported centrally of the bumper ring, and an anchor line reeved through the mast head, bumper head and said guide ring.

30 8. An airship mooring mast embodying
a mast, a mast head rotatable on a vertical axis at the top of the mast, a bumper head pivotally mounted on the mast head on a horizontal axis, a bumper ring carried by
35 said bumper head, a guide ring supported

centrally of the bumper ring, yieldable supporting means for said guide ring, and an anchor line reeved through the mast head, bumper head and said guide ring.

9. An airship mooring mast embodying
40 a mast, a hollow mast head rotatable on a vertical axis at the top of the mast, a hollow bumper head pivotally mounted on the mast head on a horizontal axis, an anchor line reeved through the mast head and bumper
45 head, and a guide sheave located adjacent to the pivot point of the bumper head to direct the anchor line in its running movements.

10. An airship mooring mast embodying
50 a mast, a hollow mast head rotatable on a vertical axis at the top of the mast, a hollow bumper head pivotally mounted on the mast head on a horizontal axis, an anchor line reeved through the mast head and bumper
55 head, and a guide sheave for the anchor line having its periphery working in the pitch line of said anchor line.

11. An airship mooring mast embodying
a mast, a mast head rotatable on a vertical
60 axis at the top of the mast, a bumper head pivotally mounted on the mast head on a horizontal axis, means for counterbalancing said bumper head, spider arms extending from said bumper head, a bumper ring carried by said arms, and an anchor line reeved through the mast, mast head and bumper head.

In testimony whereof I affix my signature,
VICTOR H. DILL.
